EX

#5697

UNITED STATES PATENT OFFICE.

OTTO F. FOGELSTRAND, OF KENSINGTON, CONNECTICUT, ASSIGNOR TO
HART MANUFACTURING COMPANY, OF SAME PLACE.

DESIGN FOR CHEST-HANDLE.

Specification forming part of Design No. 5,697, dated March 19, 1872.

To all whom it may concern:

Be it known that I, OTTO F. FOGELSTRAND, of Kensington, in the county of Hartford and State of Connecticut, have invented and produced a new and original Design for a Chest-Handle, of which the following is a specification:

The nature of my design is fully represented in the accompanying engraving, to which reference is made.

A represents the base, in which are the screw-holes for securing the device in place. B represents the handle hanging pendently therefrom. C represents an elevation on the

base A, the top of which elevation is ornamented by a row of points, as shown.

The sides of the handle B and faces of the parts A C are ornamented by raised work. The remaining surface (except a small portion in the central part of the raised figures) is covered by small triangular figures, as shown.

I claim as my invention—

The design for a chest-handle, substantially as shown.

OTTO F. FOGELSTRAND.
